UNITED STATES PATENT OFFICE

FRANCIS J. CATTERLIN, OF LOS ANGELES, CALIFORNIA

DESIGN FOR A TOY BIRD

Application filed October 21, 1930. Serial No. 37,336. Term of patent 3½ years.

To all whom it may concern:

Be it known that I, FRANCIS J. CATTERLIN, a citizen of the United States, and a resident of Los Angeles, Los Angeles County, California, have invented a new, original, and ornamental Design for Toy Bird, of which the following is a specification, reference being had to the accompanying drawings, forming a part thereof.

In the drawings Figure 1 is a side elevation

of a toy bird showing my new design, both sides being the same, including a fragmentary showing of a handle; and

Figure 2 is a front or edge view of the same.

The shading indicates contrasting colors.

I claim:

The ornamental design for a toy bird, substantially as shown and described.

FRANCIS J. CATTERLIN.
